UNITED STATES PATENT OFFICE.

OSCAR GASSETT AND ISRAEL FISHER, OF BOSTON, MASS., ASSIGNORS TO
THE UNION ELECTRIC SIGNAL COMPANY.

RAILWAY SIGNAL APPARATUS.

SPECIFICATION forming part of Letters Patent No. 233,612, dated October 26, 1880.
Application filed March 20, 1880. (No model.)

To all whom it may concern:

Be it known that we, OSCAR GASSETT and ISRAEL FISHER, both of Boston, county of Suffolk, State of Massachusetts, have invented 5 an Improvement in Railway Signal Apparatus, of which the following description, in connection with the accompanying drawings, is a specification.

Our invention relates to an automatic signal apparatus for railways, and is embodied 10 in a machine controlled by an electro-magnet, and adapted to show a signal or banner in one position while a train is on a section of track to be protected by the said signal, and to 15 place the said signal in another position when the said section of track is free to be entered upon by a train.

The machine is intended to be controlled by 20 an electro-magnet placed in an electric circuit with the rails of the track, the said magnet being demagnetized by shunting or short-circuiting it by the wheels and axles of a train, or otherwise, the battery-circuit remaining 25 constant, except when accidentally broken, as by the breaking of a rail, or washing out of the track, or rupture of a wire, or otherwise.

The present invention is based on a machine invented by Oscar Gassett, on which an application for patent filed August 14, 1879, 30 is now pending, in which a signal-machine actuated by a weight is controlled by a detent operated by the armature of an electro-magnet in such manner that the mechanism is stopped with the signal in one position when 35 the said armature is attracted to its magnet, and in the other position when the said armature is released by the demagnetization of its magnet. In both that machine and the present the signal-banner is shown as turning 40 on an axis in its plane, and indicating one condition of the block-section when the plane of the said signal is parallel with, and the other condition when perpendicular to, the line of railway, and both sides being alike, a quarter-revolution is sufficient to change the signal, 45 the edge of the signal-banner being presented to the engineer to indicate one condition of the section—as, for example, "danger," and the face thereof to indicate the opposite condition, or "safety."

The present invention consists, first, in a novel detent device, in which a vibrating detent-lever has a shoulder near its pivotal point which receives the shock and pressure of the revolving signal mechanism, the said pressure 55 acting on one side of the said pivotal point to tend to vibrate the detent-lever in one direction when the signal is in one position, and on the other side to vibrate the said lever in the other direction when in the other position. 60 The detent-lever is itself stopped from vibrating in one direction by engaging a stop on an armature-lever when the armature is attracted and held up to the poles of its electro-magnet, and is stopped from vibrating in the 65 other direction when the electro-magnet is demagnetized and the armature released. This construction removes all shock from the armature-lever and renders the pressure thereon very light, so that a weak current is sufficient 70 to control it and the signal.

The invention also consists in the construction of the stop-points on the armature-lever, whereby the said detent-lever is always caused to stop or come to rest on the proper face of 75 the stop, thereby always insuring the correct position of the signal when the controlling-armature comes to rest; also, in a stop device controlled by the actuating-power, herein shown as a spring, to stop and hold the signal in position to indicate "danger" before the 80 said actuating-power is wholly exhausted or run down; also, in an adjustable detacher for the armature-lever to press on the said lever when the armature is close to or in contact 85 with the poles of the electro-magnet, to overcome any residual magnetism when the magnet is demagnetized and insure that the armature will fall away.

Figure 1 is an end elevation of a signal-machine embodying our invention; Fig. 2, a plan thereof in one of its normal positions—that is, indicating "safety;" Fig. 3, a plan, partly in section, of a portion thereof in the other position to indicate "danger;" Fig. 4, a side view of the 90 detent-lever detached; Figs. 5 and 6, details, showing the engagement of the detent-lever with the armature-lever stops, being sections on the lines xx and yy of Figs. 2 and 3, respectively, looking toward the armature-lever; 95 100

Figs. 7 and 8, details to be referred to illustrating the operation under certain circumstances.

The actuating-power is shown as a spring, 5 *a*, attached at its outer end to a stud, *a'*, on the frame, and at its inner end to a winding-spindle, *b*, adapted to be wound by the key *b'*, from which the power is applied, in the usual way, by a ratchet, *b²*, and pawl *c*, to the large 10 driving-gear *c'*, from which the power is transmitted by the speed-increasing train *c² c³ c⁴* to the signal-shaft *d*, provided with a socket, *d'*, to receive the signal-banner, and having a tendency to rotate in the direction of the arrow, 15 Fig. 2.

The signal-shaft is provided with four arms, *e e' e' e*, at right angles to one another, shown as projecting from the socket *d'*, and provided with detent-studs *f f' f' f*, the ones *f f* being 20 farther from the axis of the shaft *d* than the ones *f' f'*. These detent-studs, flattened on their bearing side, as shown in Fig. 3, are adapted to strike on and be held by the shoulder *g* of the detent-lever *g'*, pivoted at 2 on the 25 frame-plate, the studs marked *ff* being placed to strike the said shoulder *g* on one side, and those marked *f' f'* on the other side, of its pivot 2. The studs *f* tend to vibrate the lever *g'* toward the position shown in dotted lines, Fig. 30 2, and the ones *f'* tend to vibrate it as shown in Fig. 3, and in either case if it is permitted so to vibrate, the studs *f* or *f'* will escape over the edge of the shoulder *g*, as indicated in Fig. 3, just before the lever *g'* reaches one of the 35 stop-pins 3 or 4.

The detent-lever *g'* is prevented from vibrating to release the stud *f* and arm *e* by the stop *h* on the armature-lever *h'*, pivoted at 5, and controlled by the electro-magnet *i*, the said 40 stop *h* being in position to engage the lever *g'*, as shown in Figs. 2, 5, and 7, when the armature is attracted, while the said lever *g'* is prevented from vibrating to release the stud *f'* by the stop *h²* on the said armature-lever *h'*, 45 when the electro-magnet is demagnetized and its armature permitted to fall away, being then overbalanced by the long arm of the lever *h'* on the left of the pivot 5 in Figs. 1 and 2.

The movement of the lever *h'* is limited in 50 one direction by the adjustable point *j*, and in the other by the fixed stop *j'*, shown as an insulated bracket overhanging the end of the said lever *h'*.

The magnet *i* is adjusted in proper position 55 by the screw *i'* and nut *i²*, and is retained in this position by the set-screw *i³*.

It will be observed, referring to Figs. 5 and 6, that when the detent-lever *g'* is properly engaged on the perpendicular front or stopping-face of either of its stops *h* or *h²* the other one 60 of the said stops is in position to allow the said lever to vibrate freely by it.

In Fig. 8 the armature-lever is in the same position as in Fig. 6, and consequently the lever *g'* should be in the same condition—that is, free to vibrate in the direction of the arrow 65 past the stop *h* to release one of the signal-

arms *e'*. If, however, the lever *g'* should be held by the rear side of the stop *h²*, it will be seen that the said stop would then act to prevent movement in the direction of the arrow, and thus cause one of the arms *e* to be retained 70 and a false signal given.

When, in the operation of the machine, as hereinafter described, the lever *g'* is caught 75 behind the stop *h²*, as shown in Fig. 8, and with the stud *f'* of a signal-arm, *e*, stopped on the shoulder *g*, tending to move the lever *g'* in the direction of the arrow, the inclined surface 6 of the end of the lever will bear against the 80 inclined rear surface, 7, of the stop *h²*, and the latter will yield to the pressure, thus raising the armature-lever *h'* and allowing the lever *g'* to pass in the direction of the arrow, after which the lever *h'* will drop again, the lever 85 *g'* vibrate to allow the arm *e* to escape, and then, when the shoulder *g* is struck by the stud *f'*, stop against the front face of the stop *h²* and hold the arm *e'* as in Fig. 6, thus giving 90 the correct signal.

Fig. 7 illustrates the operation when the detent-lever *g'* is caught behind the stop *h*. In this case, if the stop *h* were rigidly attached to the lever *h'*, the armature would have to be pulled away from its magnet to let the lever 95 *g'* pass; but this is obviated by pivoting the stop *h* at 8, so that it may drop down and let the said lever *g'* pass, after which it is immediately raised by the spring 9, Fig. 5, against the pin 10, to properly stop the detent-lever *g'* 100 on its front face.

The detacher for the armature is shown as a strong spring, *k*, attached to a post, *k'*, on the frame, and adjustable by a screw, *l*, and check-nut *l'*, to bring its outer end, 11, 105 which overhangs the armature-lever *h'*, into proper position to bear upon said armature-lever when the armature is at the end of its movement toward the poles of its magnet, in order to insure that the said armature shall 110 fall away when the magnet is demagnetized.

The circuit-wires for the electro-magnet *i* are to be attached to the insulated binding-screws 20 21, and the wires of another circuit to be controlled by the signal to operate any 115 desired instrument. Usually, a secondary signal-machine similar to the one in hand may be attached to the binding-screws 22 23, the said circuit then terminating in the flexible springs 120 *m n* on an insulating-block, *o*, the said springs 125 when left to themselves, as in Fig. 3, being separated and the circuit open.

One pair of opposite signal-arms (herein shown as the ones marked *e*) is provided with pins *p*, adapted to bear on an insulating-plate, 125 *n'*, on the spring *n*, and press the said spring provided with a contact-stud, *n²*, against the spring *m* to close the circuit. When the pins *p* are on the arms *e* this circuit is closed, while the electro-magnet *i* is charged and broken 130 when the said magnet is demagnetized; but by placing the pins on the wings *e'* the opposite condition would be the result.

The stopping device for the machine con-

sists of a hooked arm, *r*, attached to a rock-shaft, *s*, extended down between the frame-plates, and provided near the bottom with an arm, *t*, which is pressed by a light spring 5 against the outer leaf of the main actuating-spring *a*, which, as it opens out in operating the machine, swings the arm *t*, and consequently the hooked arm *r*, in the direction of the arrow, Fig. 2, until, before the spring is 10 so weak as to cease actuating the machine, the hooked end is in position to catch one of the pins *u* on the arms *e* and hold the said arms, and consequently the machine and signal, when the said arms *e* are in the position 15 occupied by the arms *e'* in Fig. 2, in which position the signal indicates "danger."

Another secondary circuit is closed when the armature is attracted between the wires 25 26, the former wire connected with the metal 20 frame, and consequently with the armature-lever, and the latter wire, 26, connected with the insulated armature-lever stop *j'*, the armature-lever being provided with a contact-stud, 27, Figs. 5 and 6, to make contact with the 25 said stop *j'*.

The operation of the machine is as follows: The signal consists of a plane disk alike on both sides—for example, red to indicate "danger"—and is so placed that one of the opposite 30 faces of the disk will be presented to the engineer, and consequently the same or "danger" signal be given, if either of the arms *e'*, which may be called the "danger-arms," is stopped by the detent device, and one of the opposite 35 edges of the disk will be presented to indicate "safety" if either of the arms *e*, or safety-arms, is stopped. When the magnet *i* is vitalized, the armature is attracted, and the machine comes to rest with the end of the detent-lever *g'* resting 40 against the stop *h*, and one of the detent-studs *f* of one of the safety-arms *e* bearing on the shoulder *g*. In this position the circuit-closer *m n* is closed by the pin *p*. If the magnet is 45 demagnetized, the stop *h* drops from the range of the end of the detent-lever *g'*, which swings against the stop-pin 3, allowing the arm *e* to escape, after which the stud *f'* of the next or danger-arm strikes the shoulder *g* and swings it back from the stop-pin 3 until its end strikes 50 the stop *h'* and is detained, thereby allowing the said arm *e'* to escape, so that the signal continues in this position until the magnet *i* is again charged, when the arm *e'* escapes and an arm, *e*, is detained.

55 When the stud *f'* of one of the danger-arms is detained, the circuit-closer *m n* is open, as shown in Fig. 3, so that if an electro-magnet of another precisely similar machine to the one shown is in a circuit controlled by the said 60 circuit-closer it will give precisely the same indications, as would, also, one in circuit with the wires 25 26.

Usually the signal is operated by a single change in the condition of the electro-magnet 65 *i*—as from magnetized to demagnetized, or vice versa—and a consequent single movement of the armature to one or the other of its stops;

but sometimes, as by the throwing of a switch, two changes are made in rapid succession, bringing the magnet back to its original condition, the armature-lever passing first from one stop to the other, and then back to the first stop. In this case the detent-lever will be released and the appropriate signal-arm escape on the first change of the magnet; but 70 it is possible that the second change may take place and the armature-lever return to its original position before the next signal-arm has reached the shoulder *g*, in which case the end of the detent-lever *g'* will be caught behind the stop that has just released it, the 75 said stop in the first movement of the armature-lever having released the detent-lever, which would then, in the usual course of operation, come to rest against the other stop placed in 80 line therewith by the first movement of the armature-lever; but before this can happen the second movement brings the first-mentioned stop back into the line of movement of the 85 detent-lever *g'*, as shown in Figs. 7 and 8, when 90 the said stop will be moved aside to let the said detent-lever pass, as hereinbefore described, and the second arm will escape and the signal finally come to rest in its original position, as it should, since the circuit and track are now 95 in their original condition.

It will be observed that if the stops *h h'* were omitted and the machine left to run down, the detent-lever *g'* would act as an escape- 100 ment, checking and almost stopping the movement of the arms *e e'*, so that they can never strike the shoulder *g* with a momentum greater than that derived from a quarter-revolution of the shaft *d*.

The shock of stopping the machine is received by the shoulder *g*, which is a solid piece of metal with the lever *g'*, and its sustaining-pivot 2 is firmly bedded in the frame-plate, while the said lever *g* strikes and bears on the stops of the armature-lever very lightly, having no effect on its pivot 5 to make it loose, and its friction on the said stops does not appreciably resist the movement of the said lever.

It is obvious that the stopping device *r* could 115 readily be adapted to be operated in a machine actuated by a weight, the rod *t* or its equivalent being then engaged, for example, by a knot or projection on the cord or chain by which the weight is suspended.

If desired to have the signal indicate "safety" when the magnet is demagnetized, it is only necessary to turn the signal a quarter of a revolution in its socket.

We claim—

1. In a railway signal apparatus, a visual signal, a mechanical motor to place it, and detent-studs to stop it in different positions, combined with a detent-lever provided with a shoulder to engage and hold the said studs, and adapted to be vibrated in one direction under the pressure of one of the said studs engaged to hold the signal in one position, as indicating "safety," and to be vibrated in the 120 125 130 135

other direction under the stress of a stud, holding the signal in the other position, as to indicate "danger," and an electro-magnet and its armature adapted to stop the vibration of the 5 said detent-lever in one direction when attracted by, and in the other direction when released from, its magnet, substantially as and for the purpose described.

2. In a railway signal apparatus, a mechanically-actuated signal and detent-lever to stop it in different positions, an electro-magnet, and armature-lever therefor provided with a stop having a front face to engage and hold the said detent-lever when in proper position, and 15 inclined on its rear surface, to enable the detent-lever to move it aside and pass it when engaging it on its rear side, substantially as and for the purpose described.

3. A mechanically-operated signal apparatus and detent-lever to engage and stop it in different positions, combined with an armature-lever and an electro-magnet to control it, and a pivoted stop thereon to engage the said detent-lever when in proper position and prevent it from moving in one direction, but 25 adapted to be turned aside on its pivot, to allow the said detent-lever to pass by it in the other direction, substantially as described.

4. An electro-magnet and its armature and

lever therefor, adapted by its weight to draw 30 the armature away from the said magnet when demagnetized, combined with the adjustable detaching-spring adapted to be adjusted to bear on the armature-lever only when close to the poles of its electro-magnet, substantially 35 as and for the purpose described.

5. In a mechanically-actuated railway-signal, a stopping device therefor adapted to be engaged by the actuating - power, and moved thereby into position to engage and stop the 40 signal mechanism in position to indicate "danger" before the said actuating-power is wholly exhausted, substantially as described.

6. The combination, with the actuating spring, of a rock-shaft and arm thereon to be 45 engaged by the said spring to rotate the said shaft, and a hooked stop-arm to engage a pin and stop the signal mechanism when the signal is in position to indicate "danger," substantially as described.

In testimony whereof we have signed our names to this specification in the presence of two subscribing witnesses.
